UNITED STATES PATENT OFFICE.

THOMAS J. HAYES, OF ROSLINDALE, MASSACHUSETTS, ASSIGNOR TO ARBETTER
FELLING MACHINE COMPANY, OF BOSTON, MASSACHUSETTS, A CORPORATION
OF MAINE.

WORK-PRESENTING MECHANISM FOR SEWING MACHINES.

1,413,581.

Specification of Letters Patent. Patented Apr. 25, 1922.

Application filed August 1, 1917. Serial No. 183,962.

To all whom it may concern:

Be it known that I, THOMAS J. HAYES, a citizen of the United States, and resident of Roslindale, county of Suffolk, State of Massachusetts, have invented an Improvement in Work-Presenting Mechanisms for Sewing Machines, of which the following description, in connection with the accompanying drawing, is a specification, like 10 characters on the drawing representing like parts.

This invention relates to improvements in work presenting mechanism for sewing machines and the principal object thereof is to 15 provide a bender mechanism in which the thrust of the bender may be readily controlled by the operator during the operation of the machine.

In sewing machines employing bender 20 mechanism for thrusting the fabric into the path of the needle it is necessary that the bender should be elevated to the proper height upon each of its movements, otherwise the stitch taken in the work will be too 25 shallow or too deep and where, as is often the case the line of stitching crosses different thicknesses of goods it is desirable that means be provided which will enable the thrust of the bender to be adjusted or controlled so as to permit substantially the 30 same depth of penetration of the needle throughout the entire line of stitching.

In blind stitch sewing machines for fell- 35 ing a superimposed layer of material upon a base layer it is particularly desirable that such mechanism be provided, for in blind stitching the linings to garments it very frequently happens that the line of stitching runs over a pocket or some other relatively 40 thick portion of the work and unless the thrust of the bender is changed the needle will penetrate too deeply into the fabric.

The main object of the present invention 45 is to provide a sewing machine, particularly a blind stitch sewing machine for felling with means under the control of the operator for varying the thrust of the bender at will during the operation of the machine, without the necessity of stopping it for the purpose 50 of adjusting the bender.

In sewing machines, particularly the blind stitch type of sewing machine for felling a superimposed layer upon a base layer of material it is desirable that means shall be pro-

vided for permanently adjusting the thrust 55 of the bender to accord with the thickness of the greater portion of the material which is to be operated upon.

Another object of the invention is to provide a supplemental means for adjusting or 60 controlling the thrust of the bender which will permit the position of the bender to be changed temporarily when the stitch forming mechanism is operating upon an extended relatively thick portion of the material and thereafter to be restored to its original position without interfering with the permanent adjustment of the bender and without the necessity of stopping the machine.

Other objects and features of the invention 70 will more fully appear from the following description and the accompanying drawings and will be pointed out in the annexed claims.

The embodiment of the invention is illus- 75 trated herein as applied to the work presenting mechanism of a blind stitch sewing machine of the type disclosed in my prior application Ser. No. 108,279 filed July 10, 1916 (patented March 9, 1920, number 1,383,310), in which the bender is carried by a bender supporting member preferably located beneath the bed plate of the machine and operated by a reciprocating actuating 80 member which is yieldably and adjustably connected to said supporting member.

The present invention comprises a supplemental means for varying the relative position of the bender supporting member and the bender actuating member including a disk accessible to the operator which may be rotated during the operation of the machine to effect the desired adjustment. It will be understood however, that the present invention is of a broader scope and is adapted to be applied to any form of work presenting mechanism in which it is capable of being embodied.

In the drawings;

Fig. 1 is a side elevation of a blind stitch sewing machine embodying an illustrative form of my invention,

Fig. 2 is a bottom plan view of a sewing machine bed plate illustrating a preferred 105 form of bender actuating mechanism,

Fig. 3 is a longitudinal vertical sectional view through the bed plate showing the

bender and bender actuating mechanism in elevation.

The present invention is illustrated herein as embodied in a blind stitch sewing machine of the type disclosed in my prior application No. 108,279 aforesaid, which may generally be described as of the "Arbette" type which comprises a bed plate 1, preferably provided with an upwardly projecting boss 2, forming the base for a standard 3 which carries the usual overhanging arm 4 and head 5. The main shaft 6 is journalled in suitable bearings in the standard and arm and is driven by a pulley 7 which may be clamped upon the shaft by the screw 8 or released therefrom to permit the pulley to run free for winding bobbins.

The head carries the needle actuating mechanism and complementary stitch forming mechanism and as illustrated herein comprises a needle supporting arm 9 pivotally mounted upon a shaft 10 in the upper portion of the head, the lower end of the needle supporting arm being bifurcated to provide journals 11 for a needle bar 12 carrying a curved needle. The needle bar may be and is oscillated through a link 13 actuated from the main shaft and connected to an arm 14 extending from the needle bar. A lateral or shogging movement is imparted to the needle through a cam 15 connected by a link 16 to the needle supporting arm 9, said cam being driven by a gear 17 actuated from a companion gear 18 on the main shaft.

The take-up mechanism may be of any suitable character and is not illustrated herein.

The complementary stitch forming mechanism preferably comprises a rotating loop taker located in a bracket 19 depending from the head of the machine. The hook bracket 19 also carries a presser foot 20 with which a vertically movable work support 21 operates. This work support is preferably that used in the well known type of Arbette machine and need not be illustrated herein as it forms no essential part of the present invention.

The work presenting mechanism may comprise any suitable form of mechanism for advancing the goods and any suitable bender mechanism with which my invention may be associated. Inasmuch as the work feeding mechanism has no connection with the present invention, no specific form of feeding mechanism has been illustrated herein.

The preferred embodiment of the invention illustrated herein comprises a bender 22 which is rigidly secured to one end of a bender supporting member 23 which preferably is pivoted at its opposite end upon a shaft or pin 24 which is mounted in the lower portion of the boss 2 which extends upwardly from the bed plate so that the pivotal point of the bender supporting mem-

ber is substantially upon a level with the normal position of the end of the bender.

The length of the bender supporting member preferably is such that the work engaging end of the bender will move substantially normal to the plane of the bed plate and work support.

As illustrated herein the bender is L-shaped in form having an extension 25 which is rigidly secured by screws 26 to the end of the bender supporting member 23, suitable dowel pins 27 being also employed to provide a more rigid construction between the bender and its supporting member.

The bender supporting member 23 is reciprocated by a bender actuating member which preferably is yieldably and adjustably connected to it, suitable means being provided for reciprocating said actuating member. The preferred form of actuating member which is illustrated herein comprises a lever 28 which is pivotally mounted at one end preferably upon the same shaft 24 which forms a pivot for the bender supporting member 23, and is actuated by a cam which engages oppositely disposed ways upon said actuating lever. The bender actuating lever 28 is provided at its opposite end with a laterally extending boss 29 in which an adjusting screw 30 is seated, said adjusting screw being provided with an extension 31 of decreased diameter which passes freely through an ear 32 projecting from the bender supporting member beneath the boss 29. The lower end of the screw threaded portion 30 provides a shoulder 33 which may be adjusted downwardly to engage the ear 32 of the bender supporting member and serve as an adjustment for the height to which the bender may be raised so that the bender may be adjusted for different thicknesses of goods, the uppermost elevation of the bender being limited by the contact of the ear 32 with the boss 29 so that the bender cannot be raised into the path of the needle.

The yieldable connection between the bender supporting member and the bender actuating lever may be located in any desired position but preferably is in proximity to the bender.

In the construction disclosed herein the bed plate is provided with a cup shaped recess 34 through which the end of the adjusting screw 30 extends, said screw being provided with a knurled nut 35 by means of which it may be adjusted by the operator. The actuating member or lever 28 may be reciprocated in any suitable manner but preferably is operated by a cam 36 mounted upon a shaft 37 extending transversely of the machine frame and carried by bosses 38 and 39 depending from the under surface of the bed plate.

The actuating lever 28 is provided with laterally extending ears or flanges 40, 41 to which wear plates 42, 43 are secured and the cam 36 fits closely within the space between said wear plates 42, 43 so that the actuator, and consequently the bender, is given a positive movement in both the upward and downward directions and the range of movement of the bender thereby accurately determined. The cam 36 has an extended hub 44 which is secured to the shaft 37 by a suitable set screw or a tapered pin 45. The shaft 37 is rotated through a train of gears comprising a mitre gear 46 having a hub 47 secured to the shaft 37 and co-operating gear 48 having a hub 49 secured to a shaft 50 extending longitudinally of the machine. The shaft 50 is journalled in suitable bearings 51 and 52 secured to the under face of the bed plate and upon its end is provided with an arm 53 which is connected by a link 54 to an arm 55 upon the end of a shaft 56 which is mounted in suitable bearings 57, 58 secured to the under side of the bed plate.

The axis of the shaft 56 preferably extends parallel to but is offset from the axis of the shaft 50, and the arms 53, 55 and link 54 are of such length and construction as to give the bender shaft 50 a differential rotation relatively to the shaft 56. By reason of this construction the bender cam 36 is given a relatively long dwell during the time the bender raises the work to present it to the needle and also during the time in which the bender is depressed to permit the feeding forward of the work.

Furthermore by this construction the bender is quickly removed from the path of the feeding mechanism and all interference between the bender and feeding mechanism avoided.

The shaft 56 is rotated through a spiral gear 59 which is engaged by a complementary spiral gear 60 upon the lower end of a shaft 61 which is journalled in bearings in the standard and has at its upper end a bevelled gear 62 engaging a complementary gear 63 upon the main shaft of the machine.

The mechanism thus described is substantially identical with that disclosed in my prior application No. 108,279 aforesaid. In the mechanism thus described the bender actuating member or lever 28 is positively reciprocated a predetermined amount by the cam 36 and the bender supporting member 23 is correspondingly reciprocated through the connection formed by the screw 30 which is seated in the boss 29 of the bender actuating lever, the lower end of said screw engaging the ear 32 upon the bender supporting member.

The helical spring which encircles the extension 31 of the screw 30 permits the bender to yield temporarily whenever the

bender encounters an obstruction such as a thicker seam but this yielding movement of the bender is to compensate for incidental variations of the material upon which it operates and is likely to thrust too much of the work into the path of the needle when an extensive thick portion of the work, such as a pocket is presented to the stitch forming mechanism.

The present invention contemplates the provision of supplemental mechanism which may be readily controlled by the operator for varying the position of the bender when a greater thickness of goods is presented to the stitch forming mechanism during the sewing of a garment.

The preferred mechanism for accomplishing this purpose which is illustrated herein comprises a disk 64 which is rotatably secured to the bender actuating lever 28, said disk having an eccentric portion or cam 66 which is engaged by one end of a link 67 the opposite end of said link being connected to a rocker arm 68 which is pivotally mounted upon a stud 69 seated in an extension 70 projecting downwardly from the bender supporting member 23.

The upper end of the rocker arm 68 desirably is provided with an antifriction roller 71 which engages the lower edge of the bender actuating lever 28. The axis of the rocker arm 68 is normally oblique to a link perpendicular to the lower edge of the actuating lever 28 so that as the disk 64 is rotated in the direction of the arrow, (Fig. 100 2) the rocker arm 68 will be brought toward a position normal to the plane of the lower edge of said lever and consequently will force the bender supporting member downwardly relative to the bender actuating lever, thus separating the ear 32 from contact with the ear 29 or the shoulder 33 upon the screw 30, if the latter is in an adjusted position other than that illustrated in Fig. 3 of the drawing.

By reason of this construction the operator is enabled to readily adjust the height of the bender during the operation of the machine for it is only necessary to rotate the disk 64 in the direction of the arrow to cause the bender to be lowered in the manner aforesaid and this may be accomplished just as a relatively thick portion of the work, such as a pocket is presented to the stitch forming mechanism. When in the progress of the work, the relatively thin portion is again presented to the stitch forming mechanism the operator can rotate the disk in the reverse direction and restore the bender to its normal position without stopping the machine and without interfering with the normal adjustment of the bender which is fixed by the adjusting screw 30.

It is desirable that this reverse movement 130

of the disk 64 be limited so that the operator will know when the bender has been restored to its normal position and this is accomplished in the preferred embodiment 5 of the invention illustrated herein by placing a pin 72 in the path of the link 67. This pin may conveniently be secured to the bender actuating lever 28 as illustrated in Figs. 2 and 3. The disk 64 may be provided with 10 suitable graduations which will enable the operator to determine instantly the position of the bender when the same is depressed by the rotation of the disk 64 and if desired suitable means may be provided for arresting 15 the rotation of the disk at a predetermined adjustment.

The disk 64 preferably is provided with a series of notches which are adapted to be engaged by a pawl 73 to hold the disk in 20 any desired adjusted position.

It will be understood that the particular embodiment of my invention disclosed herein is illustrative and is not restrictive and that the invention contemplates any 25 means for controlling this or any other form of bender mechanism within the meaning and scope of the following claims.

Having thus described my invention what I claim as new and desire to secure 30 by Letters Patent is:

1. Work presenting mechanism for sewing machines comprising a bender, a bender supporting lever, a bender actuating member and means for reciprocating the same, 35 means yieldably connecting said bender supporting lever and said actuating member and manually adjustable means acting upon said bender actuating lever and bender supporting member operable during the operation 40 of the machine for varying the relative positions of said bender supporting lever and said bender actuating member to control the thrust of the bender.

2. Work presenting mechanism for sewing 45 machines comprising a bender and bender supporting lever, a bender actuating member and means for reciprocating the same, means adjustably connecting said bender supporting lever and said actuating member whereby the position of the bender may be varied and supplemental manually 50 adjustable means acting upon said bender actuating lever and bender supporting member operable during the operation of the 55 machine for varying the relative position of said bender supporting lever and said actuating member to control the thrust of the bender.

3. Work presenting mechanism for sewing 60 machines comprising a bender, a bender supporting lever, a bender actuating member and means for reciprocating the same, means yieldably connecting said bender supporting lever and said actuating member to cause said bender actuating member to

reciprocate said bender supporting lever and manually operable means including a cam acting upon said bender actuating lever and bender supporting member operable during the operation of the machine for 70 varying the relative positions of said bender supporting lever and said actuating member whereby the thrust of the bender may be readily controlled by the operator.

4. Work presenting mechanism for sewing 75 machines comprising a bender, a bender supporting lever, a bender actuating member and means for reciprocating the same, means yieldably connecting said bender supporting lever and said actuating member to cause said bender actuating member to reciprocate said bender supporting lever and manually operable means including a cam carried by said bender actuating member for varying the relative positions of 80 said bender supporting lever and said actuating member whereby the thrust of the bender may be readily controlled by the operator.

5. Work supporting mechanism for sewing 90 machines comprising a bender, a pivotally mounted bender supporting member, a bender actuating lever, means yieldably connecting said bender supporting member to said actuating lever, means for reciprocating said lever, a cam rotatably mounted upon said bender actuating lever, manually operable means for rotating said cam and means operable by said cam to change the relative positions of said bender supporting 95 member and said actuating lever.

6. Work supporting mechanism for sewing 100 machines comprising a bender, a pivotally mounted bender supporting member, a bender actuating lever, means yieldably connecting said bender supporting member to said actuating lever, means for reciprocating said lever, a cam rotatably mounted upon said bender actuating lever, manually operable means for rotating said cam, a 110 rocker arm pivotally mounted upon said bender supporting member adapted to engage said actuating lever and means connecting said cam to said rocker arm whereby the rotation of said cam will cause the 115 rocker arm to vary the relative positions of said bender supporting member and said actuating lever.

7. In a blind stitch sewing machine comprising a bed plate, an overhanging arm 120 supported thereby, a needle and complementary stitch forming mechanism and means for actuating the same carried by said overhanging arm; work presenting mechanism including a bender projecting through the 125 bed plate and means for actuating said bender located below the bed plate, said means comprising a bender supporting lever, a bender actuating lever, means yieldably connecting said bender supporting le- 130

ver and said bender actuating lever and means independent of said connecting means manually operable from above the bed plate for varying the relative positions of said 5 bender supporting lever and said bender actuating lever whereby the thrust of the bender may be readily controlled.

8. In a blind stitch sewing machine comprising a bed plate, an overhanging arm 10 supported thereby, a needle and complementary stitch forming mechanism and means for actuating the same carried by said overhanging arm; work presenting mechanism including a bender projecting through the 15 bed plate and means for actuating said bender located below the bed plate, said means comprising a bender supporting lever, a bender actuating lever, means yieldably and adjustably connecting said bender supporting 20 lever, a bender actuating lever, means yieldably connecting said bender supporting lever and said bender actuating lever and means independent of said connecting means manually operable from above the bed 25 plate for varying the relative positions of said bender supporting lever and said bender actuating lever whereby the thrust of the bender may be readily controlled.

9. In a blind stitch sewing machine comprising a bed plate, an overhanging arm supported thereby, a needle and complementary stitch forming mechanism and means for actuating the same carried by said overhanging arm; work presenting mechanism including a bender projecting through the bed plate and means for actuating said bender located below the bed plate, said means comprising a bender supporting lever, a bender actuating lever, means yieldably and adjustably 40 connecting said bender supporting lever and said bender actuating lever and means independent of said connecting means manually operable from above the bed plate for varying the relative positions of said bender 45 supporting lever and said bender actuating lever whereby the thrust of the bender may be readily controlled without varying the adjustment of said connecting means.

10. In a blind stitch sewing machine comprising a bed plate, an overhanging arm supported thereby, a needle and complementary stitch forming mechanism and means for actuating the same carried by said overhanging arm; work presenting mechanism 55 including a bender projecting through the bed plate and means for actuating said bender located below the bed plate, said means comprising a bender supporting lever extending longitudinally of the bed plate, a 60 bender actuating lever extending in parallelism therewith, means yieldably and adjustably connecting the free end of said bender actuating lever to said bender supporting lever, means independent of said 65 connecting means carried by said levers and

operable from above the bed plate to vary the relative positions of said bender supporting lever and said actuating lever whereby the thrust of the bender may be readily controlled by the operator.

11. In a blind stitch sewing machine comprising a bed plate, an overhanging arm supported thereby, a needle and complementary stitch forming mechanism and means for actuating the same carried by said overhanging arm; work presenting mechanism including a bender projecting through the bed plate and means for actuating said bender located below the bed plate, said means comprising a bender supporting lever and a bender actuating lever pivotally mounted upon a common axis, means adjustably and yieldably connecting the said bender actuating lever to said bender supporting lever, a rotatable cam engaging said actuating lever and supplemental bender controlling means including a cam mounted upon said actuating lever, a rocker arm mounted upon said bender supporting lever and engaging said actuating lever, a link 85 connecting said cam to said rocker arm and a disk for rotating said cam projecting above the bed plate in a position accessible to the operator.

12. In a blind stitch sewing machine comprising a bed plate, an overhanging arm supported thereby, a needle and complementary stitch forming mechanism and means for actuating the same carried by said overhanging arm; work presenting mechanism including a bender projecting through the bed plate and means for actuating said bender located below the bed plate, said means comprising a bender supporting lever and a bender actuating lever pivotally mounted upon a common axis, means adjustably and yieldably connecting the said bender actuating lever to said bender supporting lever, a rotatable cam engaging said actuating lever and supplemental bender 100 controlling means including a cam mounted upon said actuating lever, a rocker arm mounted upon said bender supporting lever and engaging said actuating lever, a link 105 connecting said cam to said rocker arm and a disk for rotating said cam projecting above the bed plate in a position accessible to the operator, and means positioned in the path of said link for limiting the movement of said disk when the relative position of 110 the bender supporting lever and the actuating lever have been restored.

13. Work presenting mechanism for sewing machines comprising a bender, a bender supporting lever, a bender actuating lever 115 located adjacent thereto and in parallelism therewith, means for reciprocating said bender actuating lever, a yieldable and adjustable connection between said supporting lever and said actuating lever located ad- 120

5 jacent the end of the latter whereby the normal position of the bender may be adjusted, and supplemental means readily accessible to the operator for varying the relative positions of the bender supporting lever and the actuating lever whereby the position of the bender may be temporarily varied.

10 14. Work presenting mechanism for sewing machines comprising a bender, a bender supporting lever, a bender actuating lever located adjacent thereto and in parallelism therewith and means for reciprocating the same, a yieldable and adjustable connection between said supporting lever and said actuating lever whereby the normal position of the bender may be adjusted and supplemental means readily accessible to the operator for varying the relative positions of the bender supporting lever and the actuating lever whereby the position of the bender may be temporarily varied and means for arresting the movement of said manually operated means when the relative position of the bender supporting means and the bender actuating means have been restored to normal.

15 15. Work presenting mechanism for sewing machines, having a bed plate, a needle and complementary stitch forming mechanism supported thereby, comprising a bender supporting lever located beneath and pivoted at one end to said bed plate and extending longitudinally thereof, a bender rigidly secured to the free end of said bender supporting lever and adapted to be projected through said bed plate in cooperative relation to said stitch forming mechanism, a bender actuating lever pivotally mounted in said bed plate and extending in parallelism with said bender supporting lever, means yieldably connecting said bender supporting lever to said bender actuating lever, and means for reciprocating the latter.

20 16. Work presenting mechanism for sewing machines, having a bed plate, a needle and complementary stitch forming mechanism supported thereby, comprising a bender supporting lever located beneath and pivoted at one end to said bed plate and extending longitudinally thereof, a bender rigidly secured to the free end of said bender supporting lever and adapted to be projected through said bed plate in cooperative relation to said stitch forming mechanism, a bender actuating lever pivotally mounted in said bed plate and extending in parallelism with said bender supporting lever, a yieldable and adjustable connection between said bender supporting lever and said bender actuating lever accessible from above the bed plate, and means for actuating said bender supporting lever.

25 17. Work presenting mechanism for sewing machines, having a bed plate, a needle and complementary stitch forming mechanism supported thereby, comprising a bender supporting lever located beneath and pivoted at one end to said bed plate and extending longitudinally thereof, a bender rigidly secured to the free end of said bender supporting lever and adapted to be projected through said bed plate in cooperative relation to said stitch forming mechanism, a bender actuating lever pivotally mounted in said bed plate and extending in parallelism with said bender supporting lever, means connecting said bender supporting lever and said bender actuating lever, and a plurality of means operable from above the bed plate for relatively adjusting said bender supporting lever and said bender actuating lever whereby the bender may be adjusted for a particular class of work and while operating thereon be temporarily adjusted to provide for abnormal conditions.

30 18. Work presenting mechanism for sewing machines, having a bed plate a needle and complementary stitch forming mechanism supported thereby, comprising a bender supporting lever located beneath and pivoted at one end to said bed plate and extending longitudinally thereof, a bender upon the free end of said lever adapted to be projected through said bed plate in cooperative relation to the stitch forming mechanism, a bender actuating lever disposed in parallelism to said bender supporting lever and yieldably connected thereto, said bender actuating lever being provided with cam engaging means, a bender cam engaged thereby, and means for actuating said cam.

35 19. Work presenting mechanism for sewing machines, having a bed plate a needle and complementary stitch forming mechanism supported thereby, comprising a bender supporting lever located beneath and pivoted at one end to said bed plate and extending longitudinally thereof, a bender upon the free end of said lever adapted to be projected through said bed plate in cooperative relation to the stitch forming mechanism, a bender actuating lever disposed in parallelism to said bender supporting lever and yieldably connected thereto, said bender actuating lever being provided with cam engaging means, a bender cam engaged thereby, and means for imparting to said cam a variable speed of rotation whereby said bender will be given quick downward and upward movement and a prolonged dwell in its uppermost position.

40 In testimony whereof, I have signed my name to this specification.

THOMAS J. HAYES.
